UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

WATER-MIXING VALVE.

Application filed March 16, 1925. Serial No. 15,955.

To all whom it may concern:

Be it known that I, ORVIS W. VALLIER, a citizen of the United States, residing at Watertown, in the county of Jefferson and 5 State of New York, have invented certain new and useful Improvements in Water-Mixing Valves, of which the following is a specification.

This invention relates to improvements in 10 water dispensing valves, designed for use in connection with baths, sinks, lavatories, and the like, and the invention relates particularly to a single valve by which cold, 15 warm and hot water may be dispensed by the use of a single control.

The object of the invention is to provide 20 a novel valve body including integral cold and hot water receiving arms, which are adapted to be constantly charged with the water pressure, and which communicate directly with the interior of the valve body. A further object is to provide a valve which is rotatably disposed in the body between the said arms, the said valve being formed 25 with a common mixing-chamber, and with ports that communicate with said chamber and are adapted to be moved into registry with said water receiving arms, the said valve being controlled by a stem, and a handle carried thereby. A further object is 30 to provide novel means for resiliently holding the valve seated in said body and for maintaining the valve and related parts truly concentric to said body. And a further 35 object is to provide adjustable means for limiting the rotary movements of the valve.

I attain these objects by the means set forth in the detailed description which follows and as illustrated by the accompanying 40 drawing in which—

Figure 1 is a top plan view of the complete mixing-valve; showing hot and cold water supply pipes, and the progressive operations of the handle. Fig. 2 is a central vertical section, taken on line 2—2 of Fig. 1; showing the construction, arrangement and operation of the valve, the latter being positioned for dispensing warm water. Fig. 3 is a horizontal section taken on line 3—3 of 45 Fig. 2; showing the reciprocable nut. Fig. 50

4 is a horizontal section, taken on line 4—4 of Fig. 2; showing the valve closed. Figs. 5, 6 and 7 are similar sectional views, taken on line 4—4 of Fig. 2; showing the step-by-step operation of the valve for selectively dispensing cold, warm and hot water. Fig. 55 8 is a broken elevational view of the valve stem. Fig. 9 is a top face view of the split spring washer. Fig. 10 is respectively a top face view and side elevation of the valve. 60 And Fig. 11 is a top face view of the adjusting member by which the seating of the valve is controlled.

In the drawing, the hollow body of the mixing-valve, comprises a globular portion 2, and an upright hollow cylindrical portion 2', the latter being normally open at its top end, and being both externally and internally threaded. 2^a represents an external 65 threaded neck that depends from the portion 2, the normal bore 2^b of said neck communicating with the valve-chamber 2^c; the neck 2^a is also counter-bored, as at 2^d. The body 2 is formed at its opposite sides with similar horizontal hollow radial arms 3 and 70 4, the said arms having their free ends formed with hollow spheres 3'—4', from which project rearwardly threaded necks 3"—4", to which cold and hot water supply 75 pipes, as 5—6, are respectively connected, by means of gland-nuts 5' and 6'. The pipes 5 and 6 are shown supported by a wall or other part A. The inner ends of the arms 3 and 4 are provided with similar ducts 3^b—4^b, which communicate with the valve chamber 2^c, the said ducts preferably aligning, as 80 shown in Fig. 2.

The mixing-valve preferably consists of a non-metallic body 7 having a cylindrical portion 7', which conforms to the normal bore of the body portion 2', and below said portion the body 7 is preferably tapered, as at 7^a to conform to the correspondingly tapered portion 7^b of the body 2, the latter being hereinafter referred to as the valve 85 chamber. The valve 7 is rotated by a stem 8, which loosely connects with the body 7', from which it extends upwardly beyond the top of the valve body and its threaded top end is fitted with a handle 9, by which the 90

valve is manipulated, as shown by full and dotted lines in Figs. 1 and 2, and by the radial arrows in Figs. 4 to 7 inclusive. Between its ends, the stem 8 is formed with an enlargement 8', which is normally disposed concentrically in an upwardly facing recess or socket 7^c of the valve body, the lower portion of the stem thence passes downwardly through a contracted bore 7^d, 5 and part-way into an enlarged concentric bore 7^e, which will be referred to as the mixing-chamber of the valve. The valve 7 is provided with a circular radial port C, and also with an elongated radial port H, 10 both of said ports communicating with the mixing-chamber 7^e. The lower end of stem 8 is perforated diametrically and is fitted with a pin 8^a, which prevents the separation of the stem and valve, when the parts are 15 assembled for work. The stem may be withdrawn from the valve 7, by rotating said part until the pin 8^a registers with similar radial ways 7^f, which are formed at the opposite sides of the bore 7^d, as shown by 20 full and dotted lines in Fig. 10. The stem 8 is held in its operative position, shown in Fig. 2, against rotation independently of the valve 7, by means of a stud 8^b carried by the enlargement 8', which is arranged to 25 engage a radial groove 7^g formed in the margin of the socket 7^c (see Figs. 8 and 10). The valve is driven by the stem 8, by means of a relatively large pin 10, which passes diametrically through the enlargement 8' (see 30 Figs. 2 and 8), and whose ends engage an upwardly facing diametric groove 7^h of the valve body. The pin 10 is usually inserted after the stem has been applied to the valve body, as shown in Fig. 2, at which time the 35 pin 8^a is positioned out of registry with the ways 7^f. When the stem and valve are in the operative position shown in Fig. 2, the pins 8^a and 10 are disposed in the same vertical plane, and the stem cannot be released 40 accidentally, but the said stem is free to move axially a short distance relatively to the valve, as shown by the spacing of the pins 8^a and 10 from the adjacent portion of the valve body (see Fig. 2). Above the 45 enlargement 8' the stem is formed with relatively coarse box-threads 8^c, which are engaged by the cylindrical portion 12' of a nut 12, the top end of said nut comprising an annular flange 12^a which is formed with 50 oppositely facing peripheral lugs or teeth 12^b, that engage and play in corresponding longitudinal grooves 2^a of the valve body. By this construction and arrangement the nut is non-rotative by the turning of the 55 stem, but said nut may move vertically in the body 2' for adjusting the valve and related parts, as will be explained below. 13 represents a sleeve that loosely telescopes the barrel 12' of the nut, the ends of said 60 sleeve being arranged to respectively engage

the top end of the valve body and the underside of the flange 12^a of the nut, as shown in Fig. 2. The sleeve 13 arrests the downward movement of the nut 12, and being longer than the barrel 12', prevents the barrel from contact with the enlargement 8' and hindering adjusting of the parts, as well as the free rotation of the stem and valve, whenever the handle 9 is moved towards the dotted positions at the left of Fig. 1, and as shown by the radial arrow in Fig. 4. When the handle is in the latter position the valve 7 is closed, as best seen in Fig. 4. Upon the flange 12^a of the nut is mounted a convex washer 14, which is bored out to loosely receive the stem 8. This washer is split, as shown in Figs. 2 and 9, for rendering it flexible, in a well-known manner. Above the washer 14 is disposed a circular adjusting member 15, having a depending threaded portion 15' that screws into the top end of the body 2', and above said threaded portion said member is formed with an annular flange 15^a, which is surmounted by a hexagon portion 15^b, for use of a wrench. The member 15 is employed for effecting the operative seating of the valve 7, when the assembling of the device takes place, and the said adjustment need not thereafter be disturbed unless the valve 80 or its seat 7^b becomes worn and leakage results.

When the valve 7 is rotated in either direction for dispensing the water the stem 8, owing to the stationary nature of the nut 12, is moved axially to whatever extent may be required, for effecting the full right and left swing of the handle 9, as indicated in Fig. 1. This is accomplished by reason of the looseness of the stem, as explained. When the valve 7 and its stem 8 are constructed, the depth of the socket 7^c, as well as the location of the enlargement 8' of the stem, are calculated with sufficient accuracy to determine the proper range or distance the handle should be moved towards the right, for example, for dispensing first cold, then warm, then hot water, and finally for closing the valve, as shown by the dotted lines in Fig. 7. This swinging of the handle clockwise (because of the right-hand threads 8^c) moves the stem 8 downwardly until the enlargement 8' makes contact with the bottom of the socket 7^c. This stops the endwise and rotary movement of the stem and also stops the valve, with the ports C and H closed, as shown in Fig. 4. The tension exerted by the washer 14, holds the valve 7 in its tapered seat, with sufficient force for preventing leakage of the water, which has a normal pressure usually of 60 to 80 pounds, while the valve is in the idle or closed position. While the handle is being moved counter-clockwise to the closed position, shown by dotted lines in Fig. 7,

and at 9° in Fig. 1 the stem 8 is moved axially in the opposite direction by the threads 8^c, the distance allowed by the pin 8^a, which effects the positive stoppage of 5 the stem's rotation by its contact with the ledge or shoulder that forms the top or closed end of the mixing chamber 7^e. During all of the dispensing movements of the valve 7, as shown by Figs. 5-6, and by the 10 full lines in Fig. 7, the valve owing to its relatively loose connection with the stem 8, and by the accurate adjustment of member 15 operates without any appreciable grinding or wearing contact with the seat. 15 By this construction and arrangement of the parts the valve, after once being suitably ground and fitted to the seat may be operated for years without requiring redressing or grinding. Furthermore, it will 20 be readily understood that my improved valve 7 needs no packing of any kind thereby eliminating waste of water, annoyance and expense. The washer 14 is arranged to engage the flange of the nut 12 in a manner 25 to prevent wobbling of the nut, as well as the stem 8 and other parts, which might tend to cant the valve, and produce leakage or uneven wearing of the frictionally joined parts. The top end of the body 2' is preferably 30 closed by a screw cap 16, which engages the external threads of the body, the said cap serving to support and guide the stem 8. In order to prevent possible leakage around the stem, in case water should 35 well-up in the body 2', the underside of the cap is provided with a short counterbored hub 16', which is received in a corresponding socket formed in the hexagon portion of the member 15, and in this socket is disposed a 40 relatively thick greasy packing 17. When the cap and member 15 are finally adjusted and secured in place, as shown in Fig. 2, the packing 17 will last for an indefinite time 45 without requiring renewing. The handle 9 is detachably secured to the threaded upper end of the stem, by means of a nut 9'. After the mixing-valve is fully assembled, 50 as shown in Fig. 2, its operation is quite simple: Assuming that the handle 9 is in position 9^a, shown in Figs. 1 and 4, to draw cold water, the operator simply swings the handle counter-clockwise to position 9^b of Fig. 1. This brings the port C of the valve 55 into registry with the cold water duct 3^b for dispensing only cold water (see Fig. 5). To draw warm water, the operator moves the handle in the same direction, to the full line position 9^c of Fig. 1. This moves 60 the valve 7 to the position shown in Fig. 6, wherein both ports C and H are partially in registry with the ducts 3^b-4^b, which effects the mixing of the cold and hot water, for producing a tepid supply. To draw 65 only hot water, the handle 8 is again swung counter-clockwise to position 9^d of Fig. 1.

This moves the port C entirely out of registry with the duct 3^b, and moves the port H into full registry with the port 4^b (see full lines in Fig. 7). The valve 7 may then be closed for stopping the discharge of the water, by simply moving the handle a short distance in the same direction, as to position 9^e of Fig. 1. This shifts the port H entirely out of registry with the duct 4^b, as shown by the dotted lines in Fig. 7. After the hot water requirements are satisfied, the operator may swing the handle 8 clockwise to position 9^a of Fig. 1, in order that the valve may be ready for dispensing cold water at the subsequent operation.

Having thus described my invention, what I claim, is—

1. The combination with a hollow body having spaced hot and cold water receiving arms and having a valve chamber 85 communicating with said arms, and a valve rotatable in said chamber adapted to control the dispensing of the water at different temperatures of a threaded stem for rotating said valve in opposite directions, 90 means engaging the threads of the stem for limiting its rotary movements, and a spring washer mounted on said stem adapted to resiliently hold the valve in its seat and to prevent the canting of the valve and stem. 95

2. The combination with a hollow body having hot and cold water receiving arms and a valve-chamber communicating with said arms, and a valve rotatable in said chamber adapted to control the flow of 100 water from said arms into said chamber, of a stem for operating said valve, means for stopping the rotary movements of said valve, and tension means cooperating with said stopping means for thrusting the 105 valve tightly into its seat during the final closing movement.

3. The combination with a hollow body having spaced cold and hot water receiving arms, and having a valve chamber communicating with said arms, of a valve rotatable in said chamber adapted to control the flow of cold and hot water from said arms into said chamber, a stem for rotating said valve, a portion of said stem being threaded, a threaded member engaged by said threaded portion, by which axial movements of the stem are controlled, an adjusting member for holding the valve operatively seated, a tension member loosely disposed between said adjusting member and said threaded member adapted to effect the resilient seating of the valve, and a sleeve adapted to space the threaded member from the valve and to insure the free rotation of 115 the valve during the dispensing movements. 120

4. The combination with a hollow body having water receiving arms communicating with the interior of the body and having a valve chamber between said arms, of a valve 130

in said chamber, a stem for rotating said valve, an adjustable member supported by said body above the valve, a nut disposed below said member in which said stem rotates adapted to effect the reciprocation of the stem, a spring washer interposed between said nut and said member adapted to cooperate with said member for resiliently holding the valve in its seat, and means carried by the stem and engaging said valve, for controlling reciprocal as well as the rotary movement of the stem in the opposite directions.

5. The combination with a hollow body having spaced hot and cold water receiving arms and having a valve chamber communicating with said arms, and a valve rotatable in said chamber adapted to control the dispensing of the water at different temperatures, of a stem for rotating said valve in opposite directions, said stem being formed with threads beyond the valve by which the stem may be moved axially, means carried by the stem for driving the valve, means carried by the stem for preventing accidental release of the stem and for limiting axial movements of the stem relatively to the valve, said valve being formed with ports adapted to register respectively with the cold and hot water arms, means engaging the threads of the stem for effecting the axial movements of the valve in opposite directions, and means for resiliently holding the valve in its seat.

35. 6. In a water mixing device a hollow body having spaced cold and hot water receiving arms and a valve-chamber communicating with said arms, a valve rotatable in said chamber having radial ports adapted to control the flow of the water from said arms into said chamber, a stem for rotating said valve in opposite directions for dispensing cold or hot water and for mixing said waters, an adjusting member supported by said body concentric to the stem, a threaded member disposed concentric to the stem adapted to effect the axial movements of the stem towards and away from the valve, when the stem is rotated, and cushion means interposed between said adjusting member and said threaded member adapted to hold resiliently said members concentric to the stem and valve and to prevent axial movement of the valve.

55. 7. The combination with a hollow body having a valve chamber and aligning radial water inlet ducts communicating with said chamber, and a valve rotatable in said body having a mixing-chamber and radial ports adapted to register with said inlet ducts for dispensing the water, of a stem loosely and axially connected to said valve, means for interlocking said stem to the valve for limiting the axial movement of said parts relatively to each other, said stem having a

threaded portion above the valve, a means carried by said stem adapted to drive the valve, means for effecting the axial movements of the stem, and an adjustable member supported by the valve body for maintaining the seating of the valve.

8. In a valve for mixing cold and hot water, the combination with a hollow body formed with a tapered valve seat, and with water inlet ducts communicating with the chamber formed by said seat, and a tapered valve rotatable in said body having ports adapted to register with said ducts, of a reciprocable stem for operating said valve, means for loosely securing said stem to the valve body and for limiting the axial movements of the stem, said stem being formed with threads, a non-rotatable nut engaging said threads and effecting the reciprocation of the stem, an adjustable member threaded into the valve body beyond said nut, and a split spring washer interposed between said member and said nut, said washer adapted to flex and to exert its tension downwardly for resiliently seating the valve when the washer is compressed by said member.

9. The combination with a hollow body having spaced cold and hot water receiving arms and having a valve chamber communicating with said arms and a valve rotatable in said chamber adapted to control the flow of cold and hot water from said arms into said chamber, of a stem for rotating said valve a portion of said stem being threaded, said stem being loosely connected to the valve and being movable axially relatively to the valve during the opening and closing movements of the valve, means for preventing the canting of the valve and related parts, a threaded member engaging said threaded portion of the stem for effecting the reciprocation thereof, an adjustable member supported in said body for controlling the seating of the valve, means for limiting the rotary movements of said stem and valve in opposite directions, and means for preventing rotation of said threaded member.

10. In a water mixing-valve, a hollow body formed with a tapered valve-chamber and with radial ducts communicating with said chamber, means for supplying hot and cold water respectively to the said ducts, said body having a hollow discharge neck, a tapered valve rotatable in said chamber having a concentric mixing-chamber, and radial ports communicating therewith adapted to register with said ducts when the valve is rotated, said valve being bored out above said mixing-chamber and having radial ways formed in said bore, and having an enlarged socket above said ways, the opposite walls of said socket being formed with transverse aligning radial grooves, a stem disposed axially in the valve having an

enlargement adapted to loosely engage said washer interposed between said member and said nut, said washer adapted to exert its tension downwardly for resiliently thrusting the valve into its seat when said member is rotated in one direction. 10
5 socket and having threads above the enlargement, means engaging the grooves of the valve for driving the valve, a nut engaging the threads of the stem, an adjustable member threaded into the valve body for seating the valve, and a split spring.

In testimony whereof I affix my signature.

ORVIS W. VALLIER.
